(57) **CLAIM**

The ornamental design for a golf club head cover, as shown and described.

DESCRIPTION

FIG. 1 is a top perspective view of a golf club head cover; FIG. 2 is a bottom perspective view of the golf club head cover of FIG. 1;

FIG. 3 is a rear view of the golf club head cover of FIG. 1; FIG. 4 is a front view of the golf club head cover of FIG. 1; FIG. 5 is a top view of the golf club head cover of FIG. 1; FIG. 6 is a bottom view of the golf club head cover of FIG. 1;

FIG. 7 is a first side view of the golf club head cover of FIG. 1; and,

FIG. 8 is a second side view of the golf club head cover of FIG. 1.

The broken line showing is included for the purpose of illustrating and forms no part of the claimed design.

1 Claim, 7 Drawing Sheets
